KNITTING MACHINE

Martin Göttler, West Reading, Pa., assignor to
 Berkshire Knitting Mills, Wyomissing, Pa., a
 corporation of Pennsylvania

Application October 11, 1937, Serial No. 168,390.

10 Claims. (Cl. 66—96)

My invention relates to flat knitting machines and more especially to an improvement in the lock-stitch or lace making mechanism thereof.

In the use of the now common point carrying lock-stitch bar in flat knitting machines, difficulty has arisen in that operatives do not always position the bar so that the points are in proper alignment relative to the needles prior to the dipping of the lock-stitch bar to pick loops off the needles; whereas further difficulty has arisen because of failure of the operator to lock the bars into correct operative position relative to the supporting structure. Consequently, when the lock stitch bar is dipped, either a smash occurs due to the points in the bars striking the sinkers and dividers or wedging between the needles and the sinkers and dividers, or else the bar may dip without effecting transfer of the loops to other needles. Somewhat similar accidents can occur if the points in other point carrying bars are not accurately aligned at the times they are dipped to lift loops from the needles.

One object of this invention is to provide means in knitting machines whereby smashes due to points in a point carrying bar are eliminated.

Another object is to provide means whereby the points in a point carrying bar may be deflected to attract the attention of the operative in case the bar is dipped when it is not in correct position with respect to the needle bank.

Still another object is to provide an attachment which may be applied to knitting machines either when they are made, or later, and which will prevent points in a point carrying bar from striking the loop forming elements.

A further object of the invention is to provide a cam arrangement for acting on the lock-stitch shaft of a full fashioned knitting machine for deflecting the lock-stitch or lace bars to raise the lace points therein out of way of the loop forming elements such as sinkers and dividers if the lock-stitch bar is dipped when the lace points are not properly positioned with respect to the needles.

With these and other objects in view, which will become apparent from the following detailed description of the illustrative embodiment of the invention shown in the accompanying drawings, my invention resides in the novel elements, features of construction and arrangement of parts in cooperative relationship as hereinafter more particularly pointed out in the claims.

A full fashioned knitting machine in which my invention has been incorporated comprises, in addition to the necessary mechanism for making

full fashioned stockings, a group of points or groups of points for lifting loops from the needles and a means arranged to throw said points so that they do not touch any other parts of the machine when they are dipped unless said group or groups have been first properly positioned with respect to the needles.

In the drawings:

Figure 1 is a front elevational view of a full fashioned knitting machine to which my invention has been applied;

Fig. 2 is a transverse sectional view of the machine shown in Fig. 1 from which certain parts have been omitted to avoid confusion;

Fig. 3 is an elevational view on an enlarged scale of a detail portion of the machine shown in Fig. 1;

Fig. 4 is a view similar to Fig. 3 but in which the positions of certain parts have been changed;

Fig. 5 is a sectional detail view taken substantially on the line 5—5 of Fig. 3;

Fig. 6 is a view similar to Fig. 5 but showing certain parts in different positions;

Fig. 7 is a sectional view of a detail of the machine shown in Fig. 1 taken substantially on the line 7—7 of Fig. 1;

Fig. 8 is a sectional view of a detail of the machine shown in Fig. 1, taken substantially on the line 8—8 of Fig. 1;

Fig. 9 is a sectional view taken substantially on the line 9—9 of Fig. 3;

Fig. 10 is a sectional view taken substantially on the line 10—10 of Fig. 4; and

Fig. 11 is a detail view in perspective of certain parts appearing in elevation in Figs. 8 to 10 inclusive.

In the drawings and description, only those parts necessary to a complete understanding of the invention have been set forth; further information as to the construction and operation of other elements not herein specifically pointed out, but which are usual and well known, being available in the pamphlet entitled "Full Fashioned Knitting Machines", copyright 1920, and in the "Reading" Full Fashioned Knitting Machine Catalogues, copyright 1929 and 1935, published by the Textile Machine Works, Reading, Penna., and in a pamphlet entitled "Knitting Machine Lectures", published in 1935 by the Wyomissing Polytechnic Institute, Wyomissing, Pennsylvania.

The full fashioned knitting machine illustrated comprises a frame 12 of any usual or preferred form on which are a variety of parts mounted to move as required by the knitting operation and including a rotatable main cam shaft 14 arranged

to be shifted longitudinally by a chain motion mechanism 15 from knitting position to narrowing position and back again. When in knitting position, as viewed in Fig. 1, cam shaft 14, by suitable cams and connections not shown, operates the needle banks 16 to form the loops of the knitted fabric. When the cam shaft 14 is shifted to its right hand or narrowing position it operates, among other things, the lock-stitch bars 17, 17 5 or the narrowing combs (not shown), depending on which have been laid in by the operative. Each of the lock-stitch bars 17 has a series 10 of points therein, each point having a groove adapted to receive the beard of a needle and to press the beard into the needle groove when the point is passed down over the needle, the point at the same time entering between the needle and a loop thereon to lift the loop from the needle. The point can then be lifted and shifted and 15 brought down over another needle to place the loop on it. The lock-stitch bars 17 are fixed by arms 18 on a lock-stitch shaft 19 journaled in brackets 22 fixed to the front narrowing shaft 23. The bars 17 can therefore occupy either one 20 of two positions. In their one position, bars 17 are swung up against rest bar 24 and a spring latch 20 is provided on shaft 23 arranged to engage a notch 21, Fig. 7, in a collar 20a, on shaft 19 to hold bars 17 in the rest position. In their 25 other position, bars 17 are turned down immediately above the needle banks 16 for the purpose of lifting and transferring knitted loops and, when the bars 17 are in proper position lengthwise of the needle banks, latch 20 engages an elongated notch 21a in said collar to ensure and emphasize the angular position of shaft 19. When 30 down in the position shown in Figs. 1, 2 and 3, the points in bars 17 are caused to lift the loops off the needles on which the points act by dipping the front narrowing shaft 23. In the knitting position, the narrowing machine, of which shaft 23 forms a part, is supported from round idler cams 25 on cam shaft 14 by links 26, the upper ends of which are journaled on shaft 23 at 27 (Fig. 35) and the lower ends of which are pivoted to levers 28 (Fig. 2) at points 29. The levers 28 are pivoted to fixed parts of frame 12 at 30. Intermediate pivots 29 and 30, levers 28 have journaled thereto rollers 31 which rest on the idler cams 25 so long as the shaft 14 is in its knitting 40 position and the shaft 23 and bars 17 are thereby held stationary. When, however, shaft 14 has been shifted to the right from the position shown in Fig. 1 the rollers 31 are brought above narrowing cams 32 which lie alongside idler cams 25. Cams 32 are so shaped that the points in lock-stitch bars 17 are dipped below and then lifted 45 above the level of the tops of the knitting needles as rollers 31 follow the contour of cams 32. During said dipping action, the points pick off the loops on alternate needles. While the points are above the needles, the bars 17 are stepped longitudinally of needle banks 16 a one-needle distance and then dipped to place the lifted loops 50 on needles having other loops thereon. The front narrowing shaft 23 and the parts supported therefrom are guided in the dipping motions by curved arms 33 in the front ends of which shaft 23 is fixed and the rear ends of which are fixed 55 to the rear narrowing shaft 34 (Fig. 2) journaled to the frame.

The longitudinal shift of bars 17 involves a longitudinal shift of lock-stitch shaft 19. The longitudinal movement of lock-stitch shaft 19 60 may be accomplished by one of several means.

The arrangement shown for this purpose is a lace mechanism 35 (Fig. 1) of known type and generally like that disclosed in the patent to Richter No. 2,059,806, November 3, 1936. Mechanism 35 is adapted for operation numerous 65 times during the knitting of a stocking and has a standard 36 mounted to move in the direction lengthwise of shaft 19. The lock-stitch shaft 19 has an adjustable stop 37 at one end arranged to bear against the right vertical face of standard 70 36. The front narrowing shaft 23 has a vertical lever 40 pivoted thereon the upper end of which is connected to the left end of a spring 41, and the right end of which is connected to an upright arm 42 also fixed to shaft 23. The lower end of 75 lever 40 projects below its pivot point into contact with a collar 43 on shaft 19 so arranged that the spring 41 and lever 40 urge the shaft 19 toward the left as viewed in Fig. 1 to press stop 37 against standard 36. When the stop 37 is 80 against the standard as in Fig. 1, the points of bars 17 are in proper position so that a dipping action of bars 17 will lift the loops off the needles aligned with the points. Just after the points have been dipped and lifted to lift the alternate 85 loops, the lace attachment 35 pushes a cam 44 upward to press against a roller 45 on standard 36 to force shaft 19 to the right a one-needle distance.

However, means are required, or at least commonly provided, to guide the shaft 19 while being dipped and moved longitudinally. For this purpose, each of certain of the arms 48 which depend from shaft 23 for supporting the narrowing rods 46 (Fig. 5) carries a plate 47 projecting 90 below the arms while shaft 19 has a depending arm 50 for each plate 47. Each arm 50 has an upturned lower end 51 forming with the opposing lower face of arm 50 a slot 49 (Fig. 6) adapted to receive the lower end of plate 47 to guide the 95 arm 50 and thereby the shaft 19 and bars 17 during the dipping and transferring movements of shaft 19. The lower ends of plates 47 are notched at 52 as is shown in dotted lines in Figs. 3 and 4, so that the upturned ends 51 may swing 100 down through the notches to a plane at the rear of plates 47. When the operative "lays in" the lock-stitch bars he first turns them down from their upper rest position against the rest bar 24 to the position of Fig. 3. The stop 37 being against the standard 36, the ends 51 will strike the lower ends of plates 47 and the operative must then draw lock-stitch shaft 19 to the right in order that ends 51 shall enter notches 52. For this purpose, a swivelled collar 53 with 105 a handle 57 is provided on shaft 19 arranged to abut against a collar 54 fixed to shaft 19 at the right (Fig. 3) of collar 53. Collars 53 and 54 are set quite close to a bracket 22 in which shaft 19 is journaled and a screw 55 projects along the 110 front of shaft 19 toward collar 53 from the right face of bracket 22 so that a plane cam face 56 on collar 53 which slants upward from left to right when handle 57 hangs down as in Figs. 3 and 4 contacts the end of screw 55 and, when 115 handle 57 is thrown forward and upward from the position of Figs. 3 and 4, wedges between screw 55 and collar 54 to force shaft 19 to the right. The upturned ends 51 are thereby brought opposite notches 52 so that the ends 51 may drop 120 through the notches and the slots 49 may thereby be aligned with the lower ends of plates 47. Thereupon, the spring 41, aided by a coil spring 58 surrounding shaft 19, throws the shaft 19 to the left again with stop 37 against standard 125 75

36 and with plates 47 in slots 49 as shown in Figs. 3 and 5. In this position, the bars 17 lie against the front faces of the narrowing rods 46, 46 as shown in Fig. 7 and the points in bars 17 are in transverse alignment with the needles as shown in Fig. 3 and the dipping and transferring operations can be carried out rapidly and without accident.

If, however, the operative, through haste or carelessness, allows the upturned ends 51 of arms 50 to hang in the position shown in Fig. 6 in which ends 51 rest against the vertical edges of notches 52, then shaft 19 cannot move far enough to the left and the bars 17 are misplaced so that their points remain either in the misaligned position shown in Fig. 4 or, if aligned with the needles, they do not transfer the loops. If now the bars 17 are dipped, either a smash occurs due to the transfer points striking the loop forming elements known as sinkers 60 and dividers 61 or wedging between the sinkers and dividers and the needles, or the points dip and rise uselessly because they are already so far to the right that the cam 44 does not shift the shaft 19 and the bars 17 therefore are not shifted between dips to shift their points.

In accordance with my invention, such smashes and other difficulties are prevented by deflecting the lock-stitch bars from the position shown in Fig. 4, in which bars 17 are out of position, into position to attract the attention of the operative and to keep the points above the tops of the sinkers and dividers if dipped from an initial position like that of Fig. 4. In the arrangement shown, these results are accomplished automatically by providing an arm 65 fixed to the lock-stitch shaft 19 and having a rearwardly and upwardly curved rear face (Fig. 8) and a plate cam 66 having a downwardly and forwardly curved front face and adapted when parts 65 and 66 are in the same plane to cooperate with the rear face of arm 65 to turn shaft 19 counter-clockwise as viewed in Figs. 5, 6 and 7, to throw the points in bar 17 forwardly and upwardly when the shaft 19 is dipped, so that the ends of the lace points pass forwardly of the needle banks as shown in Fig. 10 and cannot strike the sinkers and dividers. As shown in Figs. 8 to 11, the cam 66 is of thin plate form 50 secured by bolts 66a and positioning pins 66b, in a vertical plane transverse to shaft 19, to a flanged cross-bar 67 fastened at its rear end by a bolt 68 used also to secure a bracket for the yarn carrier rods to the center bed 69 of the machine. The front end of crossbar 67 is bolted to the inner upper edge of the front bed 70 of the machine by bolt 71. The arm 65 and plate cam 66 are so arranged that, when the bars 17 are properly positioned with respect to the knitting needle banks, the arm 65 and cam 66 are misaligned as shown in Fig. 3 so that they do not interfere with the action of dipping bars 17, as is clear in Figs. 8 and 9, where Fig. 9 shows the parts in the same position as Fig. 3. When the bars 17 are misplaced with respect to the needle banks as shown in Figs. 4 and 10, the arm 65 overlies the cam 66, the two being in the same vertical plane transverse to shaft 19, and they coact to throw the points in bars 17 forward of the needles and free of the sinkers and dividers.

Of course, the improvements specifically shown and described by which I obtain the above results, can be changed and modified in various ways without departing from the invention herein disclosed and hereinafter claimed.

I claim as my invention:

1. In a knitting machine including two rod-like elements having cooperating movement with respect to each other which brings them into longitudinal contacting engagement, the combination with said elements of means for deflecting one of said elements relative to the other only when they are not in position for said cooperative movement.

2. In a knitting machine including two elements having complementary portions and having cooperating movement with respect to each other which brings them into longitudinal contacting engagement, the combination with said elements of means arranged to deflect one of said elements relative to the other only when they are not in position for said cooperating movement.

3. In a knitting machine including two rod-like elements each provided with interfitting engaging portions and having cooperating movement with respect to each other which brings them into longitudinal interfitting engagement, the combination with said elements of means for deflecting one of said elements relative to the other only when they are not in position for said cooperating movement.

4. In a knitting machine including two groups of loop-manipulating implements having cooperating movement with respect to each other which brings them into longitudinal contacting engagement, the combination with said elements of means arranged to swing one of said groups as a whole relative to the other only when they are not in position for said cooperation.

5. In a knitting machine having a first group of knitting implements, and a second group of knitting implements for cooperating movement with said first group, the combination of means for moving said first group towards said second group, and means for deflecting said first group of implements relative to said second group when the first group is misplaced with respect to the second group at the start of a movement caused by said moving means.

6. In a knitting machine having a needle blank, and a group of points for cooperating with the needles of said bank, the combination of means for moving said group toward said bank, and means for throwing said group forward to pass above the needles of said bank when the group is misplaced with respect to the needle bank at the start of a movement caused by said moving means.

7. In a knitting machine having a needle bank, loop-forming elements, and a bar containing points adapted to act on loops on the needles of said bank when the points are in a given position with respect to said needles, the combination of means for dipping said bar, and means for throwing said points away from said elements when the bar is misplaced with respect to the needles at the start of a dipping action.

8. In a knitting machine, in combination, a needle bank, loop-forming elements lying between the needles of the bank, a point carrying bar whose points are adapted to lift loops from said needles, a pivoted shaft on which said bar is fixed, means for advancing said bar toward said needles for lifting loops therefrom, and two members having curved cooperating surfaces one fixed with relation to said needle bank and the other fixed to said shaft and arranged to throw said bar forward on a path to prevent the points therein from striking said loop-forming elements after

said advancing means is operated when the said bar is misplaced with respect to said bank.

9. In a knitting machine, in combination, a needle bank, loop-forming elements, a lock-stitch shaft, a bar on said shaft having points thereon for cooperating with the needles of said bank to transfer stitches thereon, means for dipping said shaft, a cam arm fixed on said shaft and a cam plate in fixed relation to the plane of motion of said needle bank and adapted and arranged to cooperate with said arm to throw the point bar forwardly to move said points away from said elements whenever said bar is dipped when misplaced with respect to the needle bank.

10. In a knitting machine in combination, a point in a point bar pivotally mounted on a shaft and axially movable therealong, a needle bar having needles therein with which said point is intended to cooperate, means whereby said point bar may be locked against rotation on said shaft by said axial movement, means for moving said shaft vertically to cause the point to act on a loop on a needle, and means to deflect said bar to prevent contact of said point with a needle during said vertical movement unless the point bar is in a desired position axially of said shaft at the time it makes a downward vertical motion. 5 10

MARTIN GÖTTLER.
